UNITED STATES PATENT OFFICE.

JEFFREY T. FERRES, OF LOS ANGELES, CALIFORNIA.

CUTTING MECHANISM FOR PAPER-BOARD.

1,258,327.

Specification of Letters Patent.

Patented Mar. 5, 1918.

Original application filed November 19, 1912, Serial No. 732,288. Patent No. 1,142,409, dated June 8, 1915.
Divided and this application filed October 28, 1914. Serial No. 868,964.

To all whom it may concern:

Be it known that I, JEFFREY T. FERRES, a citizen of the United States, residing at Los Angeles, in the county of Los Angeles and 5 State of California, have invented certain new and useful Improvements in Cutting Mechanism for Paper-Board, of which the following is a specification.

My present application is a division of an 10 application for patent upon which Patent No. 1,142,409 dated June 8, 1915, for improvements in machines for making corrugated paper-board, has been issued to me, and the invention herein described and 15 claimed relates particularly to mechanism for cutting paper board such as corrugated paper board, as it is delivered from the corrugated board machine, said mechanism acting to cut the board in lengths of predetermined length. The object of my invention 20 is to provide a simple and efficient mechanism of this character which shall be capable of cutting the paper board as it is continuously being delivered by the machine 25 and without requiring any stoppage or intermittent movement of the machine.

In the drawing Figure 1 is a side elevation of the rear or delivery end of a corrugated board machine showing my cutting 30 mechanism attached thereto; Fig. 2 a detail view of the driving connections for the cutting mechanism; Fig. 3 a perspective of the cutting roll, and Fig. 4 a detail view of certain of the driving connections.

35 It will be understood that the corrugated board machine is continuous in its operation and that consequently the corrugated board is produced continuously thereon. In Fig. 1 I have shown the rear or delivery end of a 40 corrugated board machine which has produced the double-faced corrugated board marked A. The cutting mechanism is so constructed and arranged that the board will be cut with accuracy in predetermined 45 lengths while the board is being delivered from the machine.

Referring to the particular construction 50 of cutting mechanism herein shown, the same is mounted in the end frame 1 of the board machine and comprises two rolls 2 and 3 journaled in said frame. The upper roll 2, which is preferably of hardened steel or chilled cast iron, is adjustable vertically in suitable manner as by means of the adjusting screws 4 coöperating with the jour-

nal boxes 5 of the roll, these boxes being movable in vertical slots 6 in the end frame 1. The lowermost line of this roll 2 is in the plane of the top of the corrugated board.

The roll 3 is journaled directly below the 60 roll 2 and carries in its periphery one or more radially disposed knives 7 extending the length of the roll and projecting therefrom a distance to cut through the board product in coöperation with the under surface of the roll 2. In the present instance these knives are two in number but one or more may be used. For the severing of the board the roll 3 is automatically given a half turn when two knives are used or a full turn 70 when one is used.

The cutting mechanism is operated automatically by and in unison with the corrugated board machine. As herein shown the shaft 8 of the cutting roll carries a sprocket 75 wheel 9 over which extends a sprocket chain 10 which also passes over an idler sprocket wheel (not shown). The chain is provided with detachable links, all of the links being ordinarily plain links excepting those provided with lugs 11. These lugs are adapted to engage the peripheral shoulders or projections 12 of a disk 13 secured to the shaft 8. Each lug 11 is therefore adapted to engage the disk 13 so as to move it in clockwise direction (Fig. 2), thereby rotating the cutting roll 3 a half turn or full turn if two lugs are used near together. The sprocket wheel 9 is driven by the gear 14 secured thereto by bolts 15 and driven in suitable 90 manner as by means of the idler gear 16, driven by the gear 17 secured to shaft 18.

The drive is therefore from shaft 18 through gears 17 and 16 to the sprocket wheel 9, it being understood that this 95 sprocket wheel and the gear 14 are mounted loosely upon the shaft 8 while the disk 13 is secured thereto. Following the drive as far as the cutting roll, the same is through the sprocket wheel 9, chain 10, lugs 11, disk 13 100 and shaft 8. Where only one knife is used in the cutting roll additional lugs are used on the chain 10 to give it one complete turn.

In order to prevent any possibility of overthrow of the cutting roll, I key to its 105 shaft a brake drum 19 and provide a corresponding brake band 20 to which is fastened a weight 21. This brake band is connected at one end to said weight and at the other end to a fixed point 22 on the end frame. 110

Suitable driving mechanism may be employed for the roll 2 and in the present instance such mechanism comprises a gear 23 secured to the drive shaft 24, pinion 25 journaled in the end frame 1 and a gear 26 secured to the shaft 27 of the roll 2. It will be understood that the cutters are timed to move at a predetermined moment and at the same speed as the board product, with the result that the board lengths are cut uniformly, rapidly and without checking the feed of the board or causing it to buckle in front of the cutters. The board lengths may be varied by the relative position of the lugs 11 on the chain 10. By preference two iron guards 28 are placed in advance of the cutting rolls to prevent wads of paper or even the operator himself from being caught between the rolls. It will be understood that the knives in the cutter roll cut against the hardened surface of the roll 2 and sever the paper by pressure.

I claim:

1. In a machine for making corrugated board and including means for feeding the board continuously at the delivery end of the machine, a constantly rotating power driven plain smooth roll 2 on one side of the board and having the same surface speed, a rotary cutter head having radial knives arranged to cut against said plain roll, and means for actuating said cutter head at intervals.
2. In a machine for making corrugated board and including means for feeding the board continuously at the delivery end of the machine, a constantly rotating power driven plain smooth roll 2 on one side of the board and having the same surface speed, a rotary cutter head having radial knives arranged to cut against said plain roll, means for actuating said cutter head at intervals, and means for preventing overthrow of the cutter head.
3. In a machine for making corrugated board and including means for feeding the board continuously at the delivery end of the machine, a constantly rotating power driven plain smooth roll 2 on one side of the board and having the same surface speed, a cutter head having a knife arranged to cut against said plain roll, and means for

actuating said cutter head at intervals to travel at the same speed as the paper and fixed roll.

55

4. In a machine for making corrugated board, a cutting mechanism including a roll 2 on one side of the plane of the board, a rotary cutter head having radial knives co-operating with the roll, means for actuating said cutter head at intervals, and a brake device for preventing overthrow of the cutter head.

60

5. In a machine for making corrugated board, a cutting mechanism including a roll 2 on one side of the plane of the board, a rotary cutter head having radial knives co-operating with the roll, adjustable means for actuating said cutter head at predetermined intervals.

70

6. In a machine for making corrugated board, a cutting mechanism including a roll 2 on one side of the plane of the board, a rotary cutter head having radial knives co-operating with the roll, and a detachable link chain for actuating said cutter head at intervals.

75

7. In a machine for making corrugated board, a cutting mechanism including a roll 2 on one side of the plane of the board, a rotary cutter head having radial knives co-operating with the roll, and having a shaft 8, a notched disk 13 secured to said shaft, a sprocket wheel 9 loosely mounted on the shaft, means for driving such sprocket wheel, a second sprocket wheel and a sprocket chain co-operating with wheel 9, certain links of said chain having lugs adapted to co-operate and partially or completely rotate the disk and the cutter head.

85

8. In a machine for making corrugated board, a cutting mechanism including a roll 2 on one side of the plane of the board, a rotary cutter head having radial knives co-operating with the roll, means for actuating said head, and guards 28 arranged at an angle to each other and located in advance of the roll 2 and cutter head and on either side of the plane of the board.

90

JEFFREY T. FERRES.
